DESIGN FOR A DRINK MIXING CUP

Louis Myers, Galesburg, Ill., assignor to David Gensburg, Chicago, Ill.

Application July 31, 1939, Serial No. 86,391

Term of patent 14 years

To all whom it may concern:

Be it known that I, Louis Myers, a citizen of the United States, residing at Galesburg, in the county of Knox and State of Illinois, have invented a new, original, and ornamental Design for a Drink Mixing Cup, of which the following is a specification, reference being had to the accompanying drawing, forming a part thereof.

In the drawing:

I claim:

The ornamental design for a drink mixing cup, as shown.

LOUIS MYERS.
